MIXING VALVE

Rudolph Yuza, Chicago, Ill., assignor to A. Dalkin Company, Chicago, Ill., a corporation of Illinois

Application June 11, 1945, Serial No. 598,836

5 Claims. (Cl. 225—26)

1

This invention relates to certain new and useful improvements in mixing valves. More particularly the invention relates to a valve for dispensing a mixed beverage.

In this aspect of the invention, one of the principal objects is to provide a valve of this character which will be highly efficient in use and economical in manufacture.

Generally speaking, where valves of the character hereinafter described are employed for mixing beverages, in such mixture there is employed a syrup of the desired flavor. This syrup is generally admitted or drawn into a measuring chamber and thence forced under pressure into a mixing chamber, or in some instances the syrup is forced, after being drawn into the valve, into the container in which the beverage is to be served. Whichever way the syrup is admitted into the valve, it is apparent that the syrup, being of a viscous nature, has a tendency to coagulate on the operative parts or the moving parts of the valve structure, resulting in an inefficient operation of the mixing valve. Furthermore, sealing a valve of this character so as to prevent leakage thereof has always been a problem with those concerned with this art. In addition to this, it has been the aim to produce a mixing valve which will consist of the minimum number of parts.

To overcome these several known objections, it is an object to provide a mixing valve in the chambers of which there is always maintained a quantity of water and upon operation of the valve the chambers will be flushed so as to remove any surplus syrup therefrom, and as the chambers are always maintained with a quantity of water, it is clear that by capillary action leakage of the valve is prevented.

Other objects will appear hereinafter.

The invention consists in the novel combination and arrangement of parts to be hereinafter claimed and described.

The invention will be best understood by reference to the accompanying drawings showing the preferred form of construction, and in which:

Fig. 1 is an elevational view of the invention showing the valve mounted upon a supporting wall;

Fig. 2 is a vertical sectional detail view of the same;

Fig. 3 is a vertical sectional detail view similar to that shown in Fig. 1 but showing the parts in different relation with respect to each other.

The drawings illustrate the preferred form of construction by which the several objects of my invention are accomplished.

In this connection, my improved mixing valve is indicated generally at 10 and is adapted to be supported upon a wall 11 of a suitable dispensing case or enclosure. This is accomplished in a manner substantially similar to that disclosed in

2

my pending application, Serial No. 583,574, filed March 19, 1945, now Patent No. 2,456,165, dated December 14, 1948.

The method of mounting the mixing valve as disclosed in said application in general consists of providing an insulating mounting sleeve 12 confined in an opening 13 formed in a block 14 disposed within the inner and outer walls 15 of the wall 11. The valve body 16 is projected through this mounting sleeve 12, and the interior portion 16' thereof is covered by a suitable cap 17 secured as at 18 to the wall 11 and having a bead 19 formed at its inner end portion for the reception of a bezel ring 20.

The wall 21 of this cap 17 is open for the projection of the fittings 22 and 23 of the mixing valve. The inner end portion 16' of the valve body 16 is provided with a passage 24 which communicates with the fitting 22 and with a measuring chamber 25, the measuring chamber being provided between a piston 26 and the inner end portion 16' of the valve body 16. In this passage 24 there is confined what is known in the art as a "flap" valve 27.

Adjacent this passage 24, there is formed in the inner end portion 16' of the valve body, another passage 28 having a reduced portion 29 in which there is slidably mounted a plunger 30. In the enlarged portion 31 of this passage is a valve ball 32 normally urged by a spring 33 against a valve seat 34 to close communication through the passage. This valve ball 32 engages the head 35 of the plunger 30, the plunger projecting into the measuring chamber 25. The piston 26 is provided with a valve chamber 36 and in this valve chamber 36 there is mounted a flap valve 37. A port 38 opens communication between the measuring chamber 25 and the valve chamber 36. A passage 39 opens communication between the valve chamber 36 and the chamber 40.

The piston 26 is provided with a stud 41, and this stud 41 preferably is provided with an annular seat 42 which receives the flanged portion 43 of a flexible diaphragm 44. The flanged portion 45 of this diaphragm is secured in any suitable manner in a ring 46 mounted in the valve body, as shown in Fig. 2. This flexible diaphragm 42 together with the piston 26, provides the chamber 40. Communicating with this chamber 40 is an orifice 47, the outer end of which is formed in the nozzle portion 48 of the valve body 16.

A handle element 49 is supported by a shaft 50, and this shaft 50 is secured to a disc 51. This disc 51 is disposed between the plates 52 provided by the body 16 and is pivotally supported between these plates by a pivot pin 53. The disc 51 is connected to the stud shaft 41 by means of a link 54, the pivotal connection 55 between the link 54 and the disc 51 being offset with respect to the axis of the pivot pin 53.

A supply conduit (not shown) from a syrup container (not shown) is connected to the fitting 22. A supply conduit (not shown) from a water supply (not shown) is connected to the fitting 23.

In operation the handle element 49 is moved to the position shown in dotted lines in Fig. 2. This expands the diaphragm 44 and positions the piston 26 in a position to engage the plunger 30 to project the plunger inwardly to move the valve ball 32 from valve-closing position to admit an amount of water to enter the measuring chamber 25. By pivoting the handle 49 in an opposite direction or in the direction to the position shown in Fig. 3, this admitted water in the chamber 25 will find exit through the valve chamber 36 into the chamber 40, flushing and cleansing these chambers during this passage. During this operation or movement of the piston 26 in the outer direction with respect to the valve body 16, the syrup is brought into the chamber 25, the diaphragm 44 having flexed to permit the piston 26 to move in the direction of movement as shown in Fig. 3. When the piston is moved in this direction, the flap valve 31 will be closed so as to prevent the admission of syrup into the chamber 40. The piston is moved in an opposite direction, at which time the flap valve 27 opens, permitting the syrup to pass into the chamber 40 and thence into the orifice 47 into a suitable container. Continued movement of the piston rearwardly brings the piston into engagement with the plunger 30, opening the valve closed by the valve ball 32, permitting the inflow of water which passes through the valve chamber 36 and chamber 40 through the orifice 47 into the glass or container. As this water passes through the valve body 16 in the manner just disclosed, it is manifest that all the syrup is washed from within the chambers 25 and 40, leaving these chambers free of any syrup until the next operation of the valve.

In this construction of a mixing valve, it is apparent that the water serves as a seal between the moving parts, and therefore it is not necessary to employ any piston rings or seals with the piston 26. Movement of this piston 26 is free by virtue of the flexible diaphragm 44 and, by employing such a diaphragm, it is clear that in the chamber 40 there will remain a quantity of water which serves to lubricate the parts, that is, prevent the moving parts from clinging together by syrup which would otherwise coagulate within the chambers.

From the foregoing description, it is manifest that I have provided a mixing valve which accomplishes the foregoing objects and one which will be highly efficient in use and economical in manufacture.

While I have illustrated and described the preferred form of construction for carrying my invention into effect, this is capable of variation and modification without departing from the spirit of the invention. I therefore do not wish to be limited to the precise details of construction set forth, but desire to avail myself of such variations and modifications as come within the scope of the appended claims.

Having thus described my invention, what I

claim as new and desire to protect by Letters Patent is:

1. A mixing valve comprising a valve body having a plurality of passages formed therein, valve members controlling communication through said passages, a piston including a flexible diaphragm movable in said valve body and providing rearward and forward chambers, the rearward chamber communicating with the valve passages, a valve structure carried by and movable with the piston and adapted to open communication between the chambers, and means for moving said piston within said valve body.

15 2. A mixing valve including a valve body, a piston movable in the body and providing, together with an end portion of said body, a chamber, supply passages communicating with said chamber, valve passages in said chamber controlling communication therethrough, a flexible diaphragm carried by said body and providing together with said piston a chamber on the side of the piston opposite said first-named chamber, and means controlling communication between said chambers.

25 3. A mixing valve including a valve body, a piston movable in the body and providing, together with an end portion of said body, a chamber, supply passages communicating with said chamber, valve passages in said chamber controlling communication therethrough, a flexible diaphragm carried by said body and providing together with said piston a chamber on the side of the piston opposite said first-named chamber, and a valve structure carried by said piston and controlling communication between said chambers.

35 4. A mixing valve including a valve body, a piston movable in the body and providing, together with an end portion of said body, a chamber, supply passages communicating with said chamber, valve passages in said chamber controlling communication therethrough, a flexible diaphragm carried by said body and providing together with said piston a chamber on the side of the piston opposite said first-named chamber, and means controlling communication between said chambers, said means including a flap valve.

45 5. A mixing valve including a valve body, a piston movable in the body and providing, together with an end portion of said body, a chamber, supply passages communicating with said chamber, valve passages in said chamber controlling communication therethrough, a flexible diaphragm carried by said body and providing together with said piston a chamber on the side of the piston opposite said first-named chamber, and a valve structure carried by said piston and controlling communication between said chambers, said means including a flap valve.

60 RUDOLPH YUZA.
